CLAIM

The ornamental design for a garment basket, as shown and
described.

DESCRIPTION

FIG. 1 is a front perspective view of the garment basket of
the present invention, shown in a first configuration;
FIG. 2 is a front elevation view of the garment basket of the
present invention, shown in the first configuration, the rear
elevation view being a mirror image thereof;
FIG. 3 is a left-side elevation view of the garment basket of
the present invention, shown in the first configuration, the
right-side elevation view being a mirror image thereof;
FIG. 4 is a top plan view of the garment basket of the present
invention, shown in the first configuration;
FIG. 5 is a bottom plan view of the garment basket of the
present invention, shown in the first configuration;
FIG. 6 is a front perspective view of the garment basket of
the present invention, shown in a second configuration;
FIG. 7 is a front elevation view of the garment basket of the
present invention, shown in the second configuration, the rear
elevation view being a mirror image thereof;
FIG. 8 is a left-side elevation view of the garment basket of
the present invention, shown in the second configuration, the
right-side elevation view being a mirror image thereof;
FIG. 9 is a top plan view of the garment basket of the present
invention, shown in the second configuration; and,
FIG. 10 is a bottom plan view of the garment basket of the
present invention, shown in the second configuration.
The portions of the garment basket shown in broken lines
form no part of the claimed design.
